[73] Assignee: **North Central Plastics**, Ellendale, Minn.Primary Examiner—Joel Sincavage
Attorney, Agent, or Firm—Merchant & Gould P.C.[**] Term: **14 Years**

CLAIM

[21] Appl. No.: **29/087,689**

The ornamental design for an insulator for the backside of a T-post, as shown and described.

[22] Filed: **May 7, 1998**

DESCRIPTION

[51] LOC (6) Cl. **13-03**
[52] U.S. Cl. **D13/129**
[58] Field of Search .... D13/129, 131, D13/132; 174/158 F, 163 F, 175

FIG. 1 is a top plan view of an insulator for the backside of a T-post showing our new design;

FIG. 2 is a bottom plan view of the insulator;

FIG. 3 is an elevational view of one side of the insulator;
FIG. 4 is an elevational view of the opposite side of the insulator;FIG. 5 is an elevational view of one end of the insulator;
FIG. 6 is an elevational view of the opposite end of the insulator; and,
FIG. 7 is a perspective view of the insulator.

The broken line showing of the T-post is included for the purpose of illustrating environmental structure only and forms no part of the claimed design.
